CLAIM

The ornamental design for a table as shown and described.

DESCRIPTION

FIG. 1 is right side view of a table according to a first embodiment of the claimed design.

FIG. 2 is a left side view of the table of FIG. 1.

FIG. 3 is a top view of the table of FIG. 1.

FIG. 4 is a bottom side view of the table of FIG. 1.

FIG. 5 is a rear view of the table of FIG. 1.

FIG. 6 is a front view of the table of FIG. 1.

FIG. 7 is right side view of a table according to a second embodiment of the claimed design.

FIG. 8 is a left side view of the table of FIG. 7.

FIG. 9 is a top view of the table of FIG. 7.

FIG. 10 is a bottom side view of the table of FIG. 7.

FIG. 11 is a rear view of the table of FIG. 7; and,

FIG. 12 is a front view of the table of FIG. 7.

The dash-dash broken lines of the drawings illustrate portions of the table that form no part of the claimed design. The dot-dash broken lines of the drawings define the bounds of the claim and form no part of the claimed design.

The stipple shading in FIGS. 7-12 of the drawings represents contrast in appearance relative to portions without the stipple shading, although no particular color is claimed.
